UNITED STATES PATENT OFFICE.

JACOB B. OLCH, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS.

CYLINDER PAWL FOR JACQUARDS.

Application filed May 11, 1927. Serial No. 190,584.

This invention relates to improvements in jacquards for looms and it is the principal object of the invention to provide improved means for controlling the hooks which serve to give the jacquard cylinders angular movements at periodic intervals.

As ordinarily constructed jacquards are provided with one or more cylinders which are moved toward and from a series of needles. The cylinder over which a series of cards is trained moves toward the needles and certain of the latter will be depressed and others will remain unmoved according to the punching of the particular card in action. The device for successively moving the cards to position includes at least one hook which moves about a fixed center and as the cylinder moves outwardly from the series of needles the hook engages a pin or other similar device rigid with the cylinder to cause the latter to rotate on its axis. If the cylinder has four faces it is necessary that the hook and pin give the cylinder a movement of approximately 90° and during the rotary movement of the cylinder the hook will move upwardly along an arc of the movement of the cooperating pin. This slight movement of the hook has made it necessary heretofore to employ springs in the controlled devices for the hook. Where two or more hooks are employed, that is one for the top and the other for the bottom, it is customary to connect the hooks by a link and control them from a cord which hangs down within reach of the weaver. When a reversal is to be effected the cord will be moved either down or up and if moved down will be caught under a notch or other detachable holder. The cord usually is provided with a spring accommodating the aforementioned slight movement of the hooks as they move vertically under the influence of the turning pins.

It is an important object of my present invention to provide a pull means for the hooks which will obviate the necessity of the springs so that the control may be had from a card repeater corresponding in function to the so-called multipliers for box looms, this object being attained as set forth herein by the use of hooks which are positively moved in one direction by the control device and free to move in the opposite direction to accommodate the movement of the hooks under the influence of the pins.

With these and other objects in view which

will appear as the description proceeds, my invention resides in the combination and arrangement of parts hereinafter described and set forth in the claims.

In the accompanying drawings wherein a convenient embodiment of my invention is set forth,

Fig. 1 is a side elevation of a jacquard having my invention applied thereto,

Fig. 2 is a front elevation looking in the direction of arrow 2, Fig. 1 and showing the lower hook in operative position,

Fig. 3 is a vertical section on line 3—3 looking in the direction of arrows 3, Fig. 1 and showing the safety pawls,

Fig. 4 is a detailed horizontal section on line 4—4, Fig. 1,

Fig. 5 is a perspective view of the pull and safety pawls together with their control devices and,

Fig. 6 is a view indicating one form of card repeater which may be employed in connection with my present invention.

Referring to the drawings I have indicated a jacquard frame 10 and a jacquard cylinder 11 rotatably mounted on bearings 12. By means of slide rods 13 said cylinder is moved back and forth in horizontal direction in a manner well understood with those familiar with jacquard mechanisms. Each end of the cylinder is provided with a plurality of pins 14 which project longitudinally of the cylinder and afford the means by which said cylinder may be given an angular movement at periodic intervals.

I provide two sets of hooks for cooperation with the pins 14, one set being the pull over hooks and the other being the safety hooks. The upper pull over hook 20 is pivoted as at 21 to the frame 10 and has a hook end 22 which when in lowered position will operate to give the cylinder an angular movement in a counter-clockwise direction. A second hook 23 is pivoted as at 24 below the hook 20 and has a hook end 25 which when in raised operative position will give the cylinder an angular movement in a clockwise direction.

The control mechanism for said hooks 20 and 23 is shown in perspective in Fig. 5 where it will be seen that a rock shaft 30 has secured thereto a relatively long arm 31 and a relatively short arm 32. A link 33 is pivoted to the arm 31 and has a slot 34 in the upper end thereof which receives a pin 35 project-

ing from the hook 20. Said hook is weighted so that the pin 35 will normally be held against the upper end of the slot 34 by the weight of said hook. A second shorter link 36 is pivotally connected to the arm 32 and has a slot 37 in the upper end thereof which receives a pin 38 projected from the hook 23. The latter hook is provided with a counter weight 39 which serves to hold the pin 38 in the bottom of slot 37. Both of said arms 31 and 32 are secured to the shaft 30 so as to move with the latter when a flexible cord C connected to arm 31 pulls downwardly.

The safety pawls are located on that side of the jacquard opposite the pull over pawls and comprise upper and lower pawls 40 and 41 respectively which move about fixed pivots 42 and 43 respectively. A link 45 connects the pawls together and one of said pawls is extended to have connection by controlled by a jack cord 62 and actuated by means of a short link 46 with a control lever 47 secured to the rock shaft 30. Said lever 47 has attached thereto a spring S the normal action of which is to turn the shaft 30 in a clockwise direction as viewed in Fig. 5. Said pawls 40 and 41 have teeth 50 and 51 respectively which cooperate with the pins on the adjacent side of the cylinder to complete an operation to initiate the pull over hooks 20 or 23.

In Fig. 6 I have illustrated a well known form of so-called card repeater such as is shown in detail in patent to A. R. Patten, No. 578,068, issued March 2, 1897. It is sufficient for the present description to state that lever 60 of said repeater is connected to the cord C illustrated in Fig. 5 and that said lever cooperates with a chain 61 which is controlled by a jack cord 62 and actuated by a rod 63. At the desired time the lever 60 will rock to depress cord C to give the shaft 30 an angular movement in a counter-clockwise direction.

Fig. 2 illustrates another means for controlling the pull over pawls consisting of a rope 70 having a handle 71 at the lower end thereof which cooperates with a bracket 72 provided with a notch 73 by means of which the handle can be held in downward position.

In operation with the parts shown in the position indicated in Fig. 2 the cylinder will move back and forth horizontally by mechanism not shown and on each movement to the right hook 25 will engage the adjacent pin to cause the cylinder to rock about its axis. As this action takes place the pin will move downwardly with respect to its starting position so that the hook 25 will be depressed slightly. This will be accompanied by a slight rising of pin 38 in slot 37, the cord C being undisturbed by this action. When it is desired to reverse the direction in which the cards are being fed the cord C will be moved upwardly by either of the devices set forth

and spring S will act to give the shaft 30 a slight right hand rotation. The bottom of slot 37 will act to lift the weight 39 to lower the hook end 25 which was previously in action and the upward movement of link 33 will permit the weighted hook end 22 of lever 20 to fall into operative position so that as the cylinder is moved outwardly to the right from the position shown in Fig. 2 it will be given an angular movement in a counter-clockwise direction. As the hook end 22 rises the pin 35 will move downwardly in the slot 34 and the arcuate movement of the pin cooperating with said hook end about the axis of the cylinder will not disturb the cord C or the rope 70.

The safety pawls are for the purpose of moving the cylinder into proper horizontal position should the cylinder stick and not be given a complete quarter movement by the pull over pawl. As shown in Fig. 3 the cylinder is indicated as improperly thrown in dotted lines but the lower hook 51 serves to restore the cylinder to its proper position thus completing the movement which was only partly effected by the upper hook on the previous outward movement of the cylinder. Devices for assisting the safety pawls in restoring the cylinder to proper position such as spring hammers can be used but they are not illustrated herein as they are well understood and form no part of my present invention. Said safety pawls, acting only to complete the movement of the cylinder, are not required to follow the arcuate movement of the pins and it is therefore not necessary that they be permitted to rise and fall without disturbance of the cord C or the rope 70.

From the foregoing it will be seen that I have provided a control mechanism for jacquard pull over pawls so arranged that the pawls may counteract a slight rising and falling movement as the jacquard cylinder turns without disturbing the control mechanism for said pawls thus rendering unnecessary the springs and other holding devices which customarily are employed in jacquards for changing the direction of the cylinder.

Having thus described my invention it will be apparent that changes and modifications may be made therein by those skilled in the art without departing from the spirit and scope of the invention and I do not wish to be limited to the details herein disclosed, but what I claim is:

1. In a jacquard mechanism having a cylinder movable back and forth in a prescribed path and having a plurality of pull over pins, a pull over pawl having a fixed pivot, said pawl to cooperate with the pins one at a time to cause a partial rotation of the cylinder as the latter moves, a control member for the pawl, and means defining a loose connection between the pawl and the member to lift said pawl positively away from the pins when said

control member moves in one direction, said pawl being movable away from the pins independently of the control member because of the loose connection.

- 5 2. In a jacquard mechanism having a cylinder movable back and forth in a prescribed path and having a plurality of pull over pins, a pull over pawl to cooperate with the pins one at a time to give the cylinder a partial 35
- 10 rotation as said cylinder moves in one direction in its path, a fixed pivot for the pawl, a control member for the pawl, and a pin and slot connection between the pawl and the member whereby movement of the member in 40
- 15 one direction will positively move the pawl out of the path of the pins, the pawl being movable together with the pin away from the axis of the cylinder independently of movement on the part of the control member. 45
- 20 3. In a jacquard mechanism having a cylinder movable back and forth in a prescribed path and having a plurality of pull over pins, a pair of pull over pawls located on opposite sides of the axis of the cylinder, fixed pivots 50
- 25 for said pawls, a control member for the pawls movable to two positions, loose connections between the control member and the pawls, one of said pawls being operatively related to the cylinder and the other inoperatively 55
- 30 related when the control member is in one position, and the other pawl being operatively related to the cylinder when the first named pawl is inoperative relatively to the cylinder 60

other position, whereby one pawl is operatively related to the pins at a time, a pawl which is operatively related to the pins of the cylinder being movable away from the pins independently of the control member because of the loose connection. 65

4. In a jacquard mechanism having a cylinder movable back and forth in a prescribed path and having a plurality of pull over pins, a pair of pull over pawls located on opposite sides of the axis of the cylinder, fixed pivots 40

for said pawls, a control member for the pawls movable to two positions, loose connections between the control member and the pawls, one of said pawls being operatively related to the cylinder and the other inoperatively related when the control member is in one position, and the other pawl being operatively related to the cylinder when the first named pawl is inoperative relatively to the cylinder 45

when the control member is in the other position, whereby one pawl is operatively related to the pins at a time, the pawl which is operatively related to the pins of the cylinder being movable away from the pins independently of the control member because of the loose connection, and a counterweight connected to one 50

of said pawls tending normally to establish connection between the control member and said pawl. 55

In testimony whereof I have hereunto 60

affixed my signature. 65

JACOB B. OLCH.
